UNITED STATES PATENT OFFICE.

JOHN C. BERTSCH, OF NEW YORK, N. Y.

REFRIGERATING APPARATUS.

1,224,594.

Specification of Letters Patent.

Patented May 1, 1917.

Application filed June 7, 1915, Serial No. 32,605.

Renewed September 27, 1916. Serial No. 122,561.

To all whom it may concern:

Be it known that I, JOHN C. BERTSCH, a citizen of the United States, residing at New York, in the county of New York and State of New York, have invented certain new and useful Improvements in Refrigerating Apparatus, of which the following is a specification.

This invention relates to improvements in apparatus for refrigeration by the use of readily condensable fluids or vapors.

The invention is particularly intended for use in refrigerating plants or apparatus of small capacity, such as are adapted for use in residences, stores or commercial establishments, but it is to be understood that the novel features herein described are by no means limited to the type of machines mentioned, but are equally adaptable to other machines of any capacity.

The main object of the invention is to provide a cheap refrigerating apparatus which is extremely simple in construction, highly efficient in operation, and perfectly safe and durable.

Another object of the invention is to provide for an absolute separation of refrigerant and lubricant; to insure a free flow of the latter to all moving parts, and to prevent the passage of lubricant into the evaporator.

In general the invention operates on the well known compression system in which a highly volatile fluid, such as ethyl chlorid, methyl chlorid, rhigolene, or the like, is vaporized within a pipe coil, called the evaporator, for the purpose of absorbing heat from its surroundings. The gas thus formed is then compressed and discharged into another pipe coil, called the condenser, in which it is cooled and thereby liquefied for repeated use in the evaporator.

To accomplish this process I provide a rotary compressor within a casting which forms a common base for compressor and motor. The compressor body or cylinder I provide with openings which are connected to the ends of the evaporator and condenser coils, and with a flanged neck on top to which is connected a separator for the separation of compressed gas and lubricant. To the top of the separator is connected the condenser coil which forms with its lower end a receptacle for the liquid refrigerant.

The cylinder heads I provide with ports and pockets for storing a quantity of lubri-

cant, preferably anhydrous glycerin, for the lubrication of all moving parts and for sealing of all clearance spaces.

The entire apparatus comprising the compressor, separator and condenser I immerse in cooling water by means of a water jacket formed in part by the base and in part by a covered cylinder set upon the latter, for effecting the most effective cooling of all parts as well as of the refrigerant and lubricant.

The preferred construction of the invention is illustrated in the accompanying drawings, in which—

Figure 1 is a vertical section on the line 2—2 of Fig. 3.

Fig. 2 is a broken off part of a vertical section on the line 4—4 of Fig. 3, showing a modification in the construction of the separator and top or cover of water jacket.

Fig. 3 is a sectional plan view on line 5—5 of Fig. 1.

Fig. 4 is a vertical section on line 4—4 of Fig. 3, with the upper part broken off.

Fig. 5 is an enlarged longitudinal section of the stuffing box packing-gland.

Fig. 6 is a vertical section of the stuffing box on line 6—6 of Fig. 5.

The complete apparatus is preferably placed on top of the refrigerator R in order to eliminate all pipe connections; but it may be placed at any other place, with the evaporator coil connected either sidewise, behind or above the refrigerating apparatus without in the least diminishing the efficiency of the latter.

Within the base 10, which forms also the base for the motor (not shown), is placed a rotary compressor, which in its working parts may be of any well known and suitable construction, and which differs from those used heretofore in the parts hereinafter described. Over the opening 11 in the bottom of base 10 is bolted water-tight the compressor cylinder 12 which together with cylinder heads 13 and 14 differ in their construction from those used heretofore. The cylinder 12 is provided on one side with a vapor-chamber 15, on the other side with a liquid chamber 16, and on top with a flanged neck 17 which contains an outlet 18 for gas and an inlet 19 and channel 20 for lubricant, having at the bottom a similar channel 21 with drain pipe 22.

The liquid chamber 16 is provided with

inlet 23 and outlet 24 the latter being connected to one end of evaporating coil 27 by pipe 25 and regulating valve 26 which may be of any suitable construction. The other end of coil 27 (Fig. 1) is connected to vapor chamber 15 by pipe 28, all three connections 22, 25, and 28 passing through opening 11 into the open space between base 10 and refrigerator R, from whence they may be distributed in any desired direction.

10 The cylinder heads 13 and 14 contain the bearings for shaft 29 which carries the rotor 30. The rear head 13 is provided with passages 31 and ports 32 through which the lubricant stored in the front head and coming through channels 20 and 21 is distributed to the bearings and all interior parts of the rotary compressor. The front head 14 is provided with a bearing plate 33 preferably made of hardened steel and containing lubricating ports 34 and 35 (Fig. 1). Bearing plate 33 forms with head 14 an annular space 36 for storing lubricant which falls by gravity from the separator (described hereafter) through inlet 19 into channel 20 and from there into space 36 through passage 37, supplying through passage 38 channel 21 and all ports in the rear head. If desired or required for special conditions, rear head 13 may be arranged with storage space in exactly the same manner as front head 14, shown by dotted lines in Fig. 1, thereby making both heads alike; or the location of the storage space 36 may be reversed and front head 14 arranged like rear head 13, and the latter like front head 14, without in the least departing from the scope of my invention which provides practical means for the perfect and automatic lubrication of all moving parts and the sealing of all clearance spaces without using oilers, cups or other devices requiring adjustment and careful attention from the exterior of the apparatus.

45 Front head 14 is also provided with a threaded stuffing box sleeve 39 which passes through casing 40 of base 10, to which it is fastened water-tight by a threaded extension 41 and soft rubber ring 42 (Fig. 5).

50 The liquid refrigerant passes from chamber 16 through pipe 25 and regulating valve 26 into evaporator 27, which is surrounded either by water, air or brine, or by any other substance to be cooled. Whatever the surroundings of the evaporator may be, the refrigerant within the latter must abstract heat from the former, which it does by vaporizing, that is, by changing from liquid to vapor. The latter, too expensive for

60 being wasted, must be changed into liquid again for repeated use in the evaporator, which is done by removing the vapor from the evaporator coil 27 by suction through pipe 28 and chamber 15 into the compressor, where it is compressed and discharged,

together with the lubricant used for lubrication and sealing, into the separator through gas outlet 18 and discharge pipe 43.

The separator consists of a cylindrical body 44, with a flanged neck 45 at its bottom connected gas-tight to cylinder neck 17, and on top closed gas-tight by cover 46 which carries within the body 44 one or more concentric cylinders 47.

75 The mixture of superheated gas and lubricant, discharged through pipe 43 with a velocity of from 3000 to 5000 feet per minute, is thrown against the top of cylinder 47 which has a cross area of about ten times that of pipe 43, so that the velocity of the mixture within cylinder 47 is instantly reduced to from 300 to 500 feet per minute.

A still greater reduction in the velocity of the mixture, one as low as from 30 to 100 feet per minute, may be had by providing another cylinder 47a (Fig. 1) which is open at the top and forms at the bottom an integral part of body 44, being covered by a cover 48 hung to the cover 46. This reduction in velocity, assisted by the downward and then upward movement of the mixture of gas and lubricant, causes the latter, which is much heavier than the former to drop out. The lubricant is collected in the space formed by pipe 43 and neck 45, and passes through inlet 19 and channel 20 into the passages 31 and 37, and through the latter into the storage space 36. The gas, freed from lubricant, 100

and also deprived of the heat of compression by the cooling action of the body 44 and cover 46, passes through outlet 49 in the cover 46 into the condensing coil 50 in a saturated condition and is condensed in the latter by the cooling action of the water surrounding the entire apparatus.

The apparatus may be operated either on what is known as the flooded or on the dry system of compression; that is to say, the gas from the evaporator may reach the compressor in a saturated or even over-saturated condition, or in a slightly superheated condition.

In the former case the discharged gas 115 has but little superheat, whereas in the latter case the superheat may be very great. For services where but little superheat exists, the cooling of the gas within the separator is not desirable, and the body 44 is provided with a suitable non-conductive jacket 51 (Fig. 2) which may also be extended over the cover 46 if required (not shown).

But for a majority of services where more 125 or less superheat exists, the separator body 44 is provided with a liquid outlet 52 (Fig. 4) in order to pass into the lower part of condenser coil 50 the liquid which might be formed within the separator, of which 130

body 44 and cover 46 forms a part of the condenser.

The lower end of coil 50 is provided with a fitting 53, which connects with outlet 52 and liquid pipe 54, or only with the latter in case of an insulated separator body 44. (Figs. 1 and 2). The liquid pipe 54 is provided with an elbow 55 which connects with the inlet 23 of the liquid chamber 16. 10 The process of mechanical refrigeration being simply a transfer of heat from the substance to be cooled to the cooling water of the condenser, which heat is increased by the heat of compression, it is evident 15 that the efficient taking up of heat by the cooling water is a very important part of the whole process, and that it is necessary to keep all parts of the machine as well as the lubricant and liquid refrigerant as 20 cool as possible with the least quantity of water.

Based upon the law of gravitation, the warmer of two bodies of different temperatures always seeks a higher, and the colder 25 of the two a lower level. Obviously, the colder water must enter at the bottom and the warmer water run to waste on top of the apparatus, in order to run in a counter current with the refrigerant and lubricant, 30 which are the hottest on top and coldest at the bottom.

This natural law is strictly carried out in this invention, and to obtain the best results with the simplest mechanism, and at the 35 same time prevent clogging up by mud and enable the quick and easy cleaning of the water space, the whole apparatus compressor, separator, condenser, liquid refrigerant and lubricant, is immersed in water, which 40 is contained in a jacket partly formed by the base 10 and partly by a cylindrical casting 56, bolted water-tight to base 10 and covered by either a loose cover 57, as shown in Fig. 1, or a cover 58 tightly bolted to casting 56 as shown in Fig. 2.

The fresh or coldest water enters near the bottom of base 10 through inlet 59 (Fig. 4) and cools first the liquid refrigerant in chamber 16 and pipe 54, as well as the lubricant within heads 13 and 14 together with the cylinder 12. Then the gradually upward moving water cools the separator and condenser while the gas and lubricant are moving downwardly, which results in the 55 gradual increase in temperature of the cooling water and a gradual decrease in temperature of the refrigerant and lubricant. When reaching the hottest part or the top of the apparatus, the water has completed 60 its work and runs to waste, either externally through funnel 60 and outlet 61 (Fig. 1), or internally through jacket 62 and waste pipe 63 (Fig. 2).

The funnel 60 and jacket 62 are provided 65 for an equal distribution of the water over-

flow over the entire circumference of the apparatus, and also for giving the outlet 61 and waste pipe 63 a certain head pressure, thereby preventing an uneven temperature within the condenser as well as a spilling 70 of waste water, which is liable to occur with a simple water outlet near the top edge of casing 56. The bottom of base 10 is provided with a water drain 11a.

Of vital importance for the successful 75 operation of a refrigerating machine of small capacity is the proper keeping of the stuffing box, which must be provided with an automatic adjustment for different pressures, and also with means for preventing 80 the intake of air as well as the drying out of the lubricant (glycerin) in front of the stuffing box gland. An auxiliary stuffing box in front of the main-stuffing box has been proposed for this purpose, but the use 85 of such greatly increases the power required for overcoming the friction, which grows rapidly with units of small capacity and raises the power rate to a prohibitive height. To overcome these obstacles without the use 90 of an auxiliary stuffing box, I provide in front of the regular or ordinary gland 64 (Figs. 1, 5 and 6) with a sub-gland 65, which is held in place and fixed relation to gland 64 by two or more dowel pins 66. 95 Sub-gland 65 bears upon gland 64 only with a part of its surface, the other part forming a sufficient space for the free turning of an oil ring 67 upon shaft 29. The stuffing box extension 41 is provided with a screw 100 cap 68 which bears a guard 69 for the protection of the flexible coupling 70 between shaft 29 and motor shaft 71.

Between sub-gland 65 and cap 68 I place a spring 76, adjustable by screwing cap 68 105 in or out, for holding stuffing box packing 72 automatically under the proper pressure.

The receptacle 75 formed by extension 41 and screw cap 68 is filled partly with mineral oil or the like, into which is dipping 110 oil ring 67, continuously carrying oil upon shaft 29 while the latter is turning. To carry the oil partly within the gland 64, the latter is provided with a larger bore for a part of its length, forming an annular 115 space 73. A disk 74, rigidly mounted upon shaft 29, prevents the oil from reaching coupling 70 by throwing off by centrifugal force any particle of oil which might reach disk 74, and depositing same in the receptacle 75, at the bottom of which is accumulating 120 also all the glycerin which might be forced out of the stuffing box packing by pressure within the compressor.

All stop valves, pressure gages, thermostatic control and other devices, ordinarily provided with refrigerating machines of small capacity, are purposely omitted in these specifications and in the accompanying drawings, because they have been found 125 130

in most cases rather a detriment than a help to the apparatus. But if desired, these auxiliary devices may be applied to this invention in any one of the well known methods, without in the least changing the 5 *modus operandi* of the apparatus as described.

I claim:

1. In a refrigerating apparatus, the combination with a condensing conduit of a water jacket surrounding the same, said water jacket having an inlet at the bottom and an internal overflow wall in the upper part, forming an annular chamber in the 10 jacket, and an outlet from said chamber.
2. In a refrigerating apparatus, the combination of a compressor, lubricant separator, condenser and evaporator connected in series for the circulation of a refrigerant 15 through the same, and a water filled casing inclosing the compressor, the condenser and the separator, the connections to the evaporator extending through the wall of said casing.
3. In a refrigerating apparatus, the combination of a compressor, lubricant separator, condenser and evaporator connected in series for the circulation of a refrigerant 20 through the same, and a casing adapted to contain water and inclosing the compressor, the condenser and the separator, said casing comprising a hollow base with an opening in the bottom thereof and a shell supported on said base, the compressor being 25 mounted in said base over the opening, the separator and condenser being mounted on the compressor, and the connections from the compressor to the evaporator extending through said opening.
4. In a refrigerating apparatus, the combination of a compressor, lubricant separator, a condenser and an evaporator connected in series for the circulation of a refrigerant 30 through the same, the separator and condenser being supported upon the compressor casing and the evaporator being connected to said casing.
5. In a refrigerating apparatus, the combination of a separator, a condenser coil 35 surrounding the same and connected thereto, a compressor on which said separator and coil are supported and with which the separator communicates, and a water jacket surrounding the separator and the coil.
6. In combination in a refrigerating apparatus, a compressor for fluid refrigerant, a base having a cooling water compartment formed therein in which said compressor is mounted, a lubricant separator mounted 45 on said compressor and communicating with the outlet port thereof, a condenser coil surrounding the separator and communicating at the inlet end thereof with the outlet of the separator, said coil extending downwardly 55 into said compartment, an evaporator com-

municating with the outlet of the condenser coil, and with the inlet of the compressor, and a water jacket mounted on said base, surrounding said condenser coil and said separator and receiving cooling water from said 70 compartment.

7. In a refrigerating apparatus, the combination of a compressor for fluid refrigerant, a base for the compressor adapted to support a driving motor for the compressor 75 and provided with a cooling water compartment in which the compressor is located, a lubricant separator mounted on the compressor communicating with the outlet thereof, and with an internal lubricant chamber 80 formed within the compressor, a condenser mounted on and located above the compressor, surrounding the separator and communicating with the fluid outlet thereof, and with a refrigerant chamber formed within the compressor, an evaporator receiving refrigerant from said condenser, and a water jacket mounted on the base communicating with the compartment and receiving cooling water therefrom and surrounding 85 said separator and said condenser.

8. In a refrigerating apparatus, the combination of a compressor for fluid refrigerant, a base for the compressor adapted to support a driving motor for the compressor 95 and provided with a cooling water compartment in which the compressor is located, a lubricant separator mounted on the compressor communicating with the outlet thereof, a condenser surrounding the separator and communicating with the fluid outlet thereof, an evaporator receiving refrigerant from said condenser, and a water jacket mounted on the base communicating with the compartment and receiving cooling wa- 100 ter therefrom and surrounding said separator and said condenser.

9. In a refrigerating apparatus, a rotary compressor for fluid refrigerant, a base therefor having a compartment formed 110 therein in which said compressor is located and through a wall of which the shaft of the compressor projects, a lubricant separator located above the compressor and communicating with the outlet thereof, a condenser 115 surrounding the separator and communicating therewith, an evaporator communicating with the outlet of the condenser, and with the inlet of the compressor, a water jacket for the separator and the condenser 120 mounted on the base and communicating with said compartment, a cooling water inlet communicating with the compartment and a water discharge passage communicating with the upper end of the water jacket. 125

10. In a refrigerating apparatus, a rotary compressor having a refrigerant chamber and a lubricant distributing chamber formed within the walls thereof, a separator located above and mounted on the compressor and 130

communicating with the outlet of the rotary compressor and with said lubricant chamber, a condenser surrounding the separator and communicating with the fluid outlet thereof and with said refrigerant chamber, an evaporator communicating with said refrigerant chamber and with the inlet port of the compressor, and a water jacket surrounding the compressor, the separator and the condenser, provided near the bottom thereof with a cooling water inlet port and near the top thereof with a cooling water discharge passage.

11. In a refrigerating apparatus, the combination of a rotary compressor for fluid refrigerant, having an inlet port and an outlet port formed in the cylindrical portion of the compressor and having a refrigerant chamber and a lubricant distributing chamber formed within the compressor casing, a separator communicating with the outlet of the compressor and having a port communicating with the lubricant distributing chamber, a condenser communicating with the outlet of the separator and with the refrigerant chamber of the compressor, and an evaporator communicating with the refrigerant chamber and with the inlet of the compressor, all connections with the compressor being within the cylindrical wall thereof whereby the heads of the compressor are free of said connections.

12. A refrigerating apparatus comprising a compressor, a condenser, a lubricant separator communicating with the outlet of the compressor and the inlet of the condenser, an evaporator communicating with the outlet of the condenser and the inlet of the compressor, a chamber adapted to contain cooling water located above the compressor and inclosing the separator and the condenser, said separator being superimposed on the compressor and said condenser

being in the form of a coil surrounding the separator.

13. A refrigerating apparatus, comprising a compressor, a condenser, a lubricant separator communicating with the outlet of the compressor and the inlet of the condenser, an evaporator communicating with the inlet of the compressor and the outlet of the condenser, and a chamber adapted to contain cooling water located above the compressor and inclosing the condenser and the separator, the condenser and the separator being mounted on said compressor.

14. A refrigerating apparatus comprising a compressor, a condenser coil, a separator communicating with the outlet of the compressor and the inlet of the coil and surrounded by the coil, an evaporator communicating with the outlet of the coil and the inlet of the compressor, a cooling chamber inclosing the compressor, a second cooling chamber located above the compressor and inclosing the condenser and the separator, and means for passing cooling liquid in series through said chambers.

15. A refrigerating apparatus, comprising a compressor, a condenser coil, a separator communicating with the outlet of the compressor and the inlet of the coil, and surrounded by the coil, an evaporator communicating with the outlet of the coil and the inlet of the compressor, a passage formed within the casing of the compressor for establishing communication between the condenser coil and the evaporator, and a chamber surrounding the condenser and evaporator, and located above the compressor.

In testimony whereof, I affix my signature in presence of two witnesses.

JOHN C. BERTSCH.
